DESIGN FOR A GARMENT HANGER

John Bolten, Andover, Mass., and Henry Spitz,
Great Neck, N. Y.

Application July 16, 1945, Serial No. 120,770
Term of patent 14 years

(Cl. D80—8)

To all whom it may concern:

Be it known that we, John Bolten and Henry Spitz, citizens of the United States, residing respectively at Andover, county of Essex, State of Massachusetts, and at Great Neck, county of Nassau, State of New York, have invented a new, original, and ornamental Design for a Garment Hanger, of which the following is a specification, reference being had to the accompanying drawing, forming part thereof, wherein

Fig. 1 is a side elevational view of a garment hanger embodying our new design;

Fig. 2 is a vertical sectional view on line 2—2 of Fig. 1;

Fig. 3 is a horizontal sectional view on line 3—3 of Fig. 1;

Fig. 4 is a vertical sectional view on line 4—4 of Fig. 1; and

Fig. 5 is a vertical sectional view on line 5—5 of Fig. 1.

We claim:

The ornamental design for a garment hanger, substantially as shown.

JOHN BOLTEN.
HENRY SPITZ.
